(57) **CLAIM**

The ornamental design of a water bottle, as shown and described.

DESCRIPTION

FIG. 1 is a top, front, right side perspective view of a water bottle showing my new design;
FIG. 2 is a front elevation view thereof;

FIG. 3 is a back elevation view thereof;

FIG. 4 is a right side elevation view thereof;

FIG. 5 is a left side elevation view thereof;

FIG. 6 is a top, back, left side perspective view thereof;

FIG. 7 is a top, back, right side perspective view thereof;

FIG. 8 is a top, front, left side perspective view thereof;

FIG. 9 is a bottom, back, left side perspective view thereof;

FIG. 10 is a bottom, back, right side perspective view thereof;

FIG. 11 is a bottom, front, left side perspective view thereof; and,

FIG. 12 is a bottom, front, right side perspective view thereof.

1 Claim, 9 Drawing Sheets
